UNITED STATES PATENT OFFICE.

JOHN WALTER STEVENS, OF ST. PAUL, MINNESOTA.

DESIGN FOR A SEAL-PLATE FOR SEAL-LOCKS.

SPECIFICATION forming part of Design No. 28,696, dated May 24, 1898.

Application filed April 4, 1898. Serial No. 676,469. Term of patent 7 years.

To all whom it may concern:

Be it known that I, JOHN WALTER STEVENS, a citizen of the United States, residing at St. Paul, in the county of Ramsey and State of Minnesota, have produced and invented a certain new and original Design for Seal-Plates for Seal-Locks, of which the following is a specification.

This invention relates to the seal-plates employed in seal-locks, and the design thereof is illustrated in the accompanying drawings, which show, in—

Figure 1, a perspective view of the plate from one side, and Fig. 2 is a perspective view of the reverse side.

The leading feature of my design is the outline of the plate in the form herein shown and described.

Referring to the drawings by letter, A represents the body of the plate, the faces being 20 flat, and with notches or indentations B' B² formed in the side edges of the disk.

Having thus described my invention, what I claim as new is—

The design for a seal-plate for seal-locks 25 substantially as herein shown and described.

In testimony whereof I have hereunto set my hand in the presence of two subscribing witnesses.

JOHN WALTER STEVENS.

In presence of—

LEWIS D. MANN,
C. N. WOODWARD.
